UNITED STATES PATENT OFFICE

CHARLES ROBERT LIBBY, OF SYRACUSE, NEW YORK, ASSIGNOR TO THE LAMSON COMPANY, OF SYRACUSE, NEW YORK, A CORPORATION OF MASSACHUSETTS

PNEUMATIC DISPATCH CARRIER

Application filed December 8, 1930. Serial No. 500,754.

This invention pertains to an improvement in pneumatic dispatch carriers and more particularly relates to a method of attaching a skirt to one end of the carrier and to the resulting structure.

Pneumatic carriers having the type of skirt shown in the patent to Jennings, No. 1,773,360, August 19, 1930, are objectionable due to the fact that the stitches securing the skirt to the carrier are exposed and come in contact with the carrier tube during the travel of the carrier and consequently quickly wear out. A further objection lies in the method of attaching such skirt portions to the carrier body in that the resulting structure does not offer any protection to the end bumpers and cover when traveling around bends or curves in the tubes. Consequently premature repairs and replacements are necessitated and the life of the carrier is appreciably shortened.

It is the object of this invention to provide a simple and efficient method of attaching the skirt portion to the body of a carrier which will produce a durable structure and provide the necessary protection to the end and bumpers of the carrier, which will protect the stitches or other means securing the skirt to the carrier, and which is generally superior to the old type skirt portions.

Further objects and advantages will be apparent as attributes of this method of attaching such skirt portions to the carrier body and the resulting structure herein shown and described in connection with the accompanying drawings which illustrate this invention by way of example and in which;

Fig. 1 is a side elevation partly in section of one end of a carrier embodying this invention;

Fig. 2 is a front elevation of a section of the carrier shown in Fig. 1; and

Fig. 3 is a plan view of the carrier shown in Fig. 2 the cover being closed.

Referring to the accompanying drawings, and more particularly to Figs. 1 and 2 thereof, the carrier may be of any suitable type, whether the access be at the side or at one end, but is here shown, for example, as having a body portion or shell 1 of oval cross

section and the access at its end. A suitable cover 2 affording access to the interior of the carrier is secured to the body portion 1 by the hinge 5 and normally locked in place by a strap 6 and a fastener 8. The bumpers 3 and 4 are secured to the cover 2 by the rivets 7.

The skirt 10 comprises a substantially rectangular piece of leather or other suitable material having a length preferably greater than the circumference of the carrier in order to permit the sides 12 and 13 to overlap rather than butt each other. Preferably the sides 12 and 13 are skived to form a skived joint as indicated by numeral 15 in Fig. 1, rather than a lapped joint. At predetermined points adjacent to each of the edges or sides 12 and 13 circular holes 16 are provided for the reception of rivets 18. Similar holes are also provided at the center of the skirt between the sides 12 and 13 for the reception of the rivets 18. Preferably the end 11 is also skived in order to provide a skived joint with the body portion 1 as indicated by numeral 14 in Figs. 1 and 3.

The skirt 10 having been thus prepared is circumposed around the end of the carrier body with the skin or finished side facing inwardly in the position shown by the dot and dash lines in Figs. 1 and 2, and with the end 17 engaging exteriorly the body portion adjacent the opening therein. While the skirt portion is being held in this position, the ends 5^a of the hinge and 6^a of the fastener strap are inserted between the skirt and the body portion on opposite sides of the carrier body, as shown in Fig. 1. While being held in this position the portion of the skirt adjacent the end 17 is stitched or otherwise fastened to the carrier body around its entire circumference. As shown in Fig. 1, this stitching 17^a also secures the fastener strap and hinge to the body portion.

A stiffener plate 19 comprises a rectangular piece of sheet metal, for example, zinc, or other rigid material, having a length equal to the circumference of the body portion 1 and provided with holes at predetermined points for the reception of the rivets 18 and 18^a. The stiffener plate is circumposed about the 100

body portion subjacent to the end 17 of the skirt 10 and may be held in position by the rivets 18 and 18^a which, preferably at this stage of the assembly, are inserted from the 5 interior of the body portion 1. The free end 11 of the skirt is then pulled down over the stitching 17^a, forming a protuberant pocket 20, as shown in Fig. 2, and thereby bringing the finished surface of the leather to the outside. This step may be easily accomplished 10 as the overlapping sides 12 and 13 at this stage are free and do not offer the resistance they would if cemented together. At this stage it is preferable to cement the sides 12 and 13 of 15 the skirt portion. The pocket 20 is then filled with goats' hair, leather scrap or other suitable material, and is uniformly packed to provide a protuberance or swell of a desired contour around the circumference of the carrier body with the exception of the portions thereof through which the rivets 18 and 18^a project. The skirt portion is then stretched or 20 worked into position in order to permit the rivets 18 and 18^a to pass through the openings 25 16. Washers 21 are applied to the ends of each of the rivets 18 and 18^a and secured thereto in the usual manner. Having thus provided the desired contour to the skirt portion, the end 11 is stitched or otherwise secured 30 to the body portion, forming a skived joint therewith as shown by numeral 14 in Figs. 1 and 2.

From the foregoing it is apparent that this method of attaching the skirt to the carrier 35 produces a structure wherein the stitching 17 or other fastening means is completely concealed and thus protected from wear and damage thereto which would result from being exposed. It is further apparent that the 40 stitching adjacent the end 11 will be similarly protected due to the protuberance of the adjacent skirt portion. Likewise, the rivets 18 and 18^a will be protected and prevented from coming in contact with the tube through 45 which the carrier travels.

A further feature of this structure is that the protuberant portion of the skirt adjacent the cover will protect the bumpers 3 and 4 when entering a terminal or other receptacle 50 and also will prevent the bumpers from coming in contact with the carrier tube when travelling around the bends or curves therein.

While I have shown and described one desirable embodiment of this invention, I wish 55 it to be understood that the application of this method is not limited to the type of carrier here shown, that in practicing this method it is not necessary to adhere to the precise order of steps herein recommended, and that 60 various changes and modifications both in the order of steps and materials employed can be made without departing from the spirit and scope of this invention as set forth in the appended claims.

65 I claim:

1. The herein described method of attaching a skirt to a pneumatic dispatch carrier which comprises the following steps, circumposing the skirt around the carrier body, securing one end of the circumposed skirt throughout its entire length to the carrier body, pulling the opposite end of the skirt over the secured end thereof to form a protuberant pocket, and securing said opposite end throughout its length to the carrier body. 70

2. The herein described method of attaching a skirt to a pneumatic dispatch carrier which comprises the following steps, circumposing the skirt around the carrier body, securing one end of the circumposed skirt throughout the entire length to the carrier body, pulling the opposite end of the skirt over the secured end thereof to form a protuberant pocket, joining the sides of the skirt, and securing said opposite end throughout its length to the carrier body. 75

3. The herein described method of attaching a skirt to a pneumatic dispatch carrier which comprises the following steps, circumposing one end of a skirt around the carrier body and securing the same throughout its entire length to the carrier body, pulling the opposite end of the skirt over the secured end thereof to form a protuberant pocket, and securing said opposite end throughout its length to the carrier body. 80

4. The herein described method of attaching a skirt to a pneumatic dispatch carrier which comprises the following steps, skiving one end and the overlapping side portions of a skirt, circumposing the unskived end of the skirt about the carrier body and securing the same throughout its length thereto, pulling the skived end of the skirt over the secured end thereof to form a protuberant pocket, securing the overlapping skived sides to form a skived joint, and finally securing the skived end of said skirt throughout its length to the carrier body to form a skived joint therewith. 100

5. The herein described method of attaching a skirt to a pneumatic dispatch carrier which comprises the following steps, circumposing one end of a skirt around the carrier body and stitching the same throughout its entire length to the carrier body, pulling the opposite end of the skirt over the stitched end thereof to form a protuberant pocket, and stitching said opposite end throughout its length to the carrier body. 115

6. The herein described method of attaching a skirt to a pneumatic dispatch carrier which comprises the following steps, skiving the one end and the overlapping side portions of a skirt, circumposing the unskived end of the skirt about the carrier body and stitching the same throughout its length thereto, pulling the skived end of the skirt over the stitched end thereof to form a protuberant pocket, securing the overlapping 120

skived sides to form a skived joint, and finally stitching the skived end of said skirt throughout its length to the carrier body to form a skived joint therewith.

- 5 7. The herein described method of attaching a skirt to a pneumatic dispatch carrier having a stiffener plate circumposed around its body portion adjacent to one end thereof, which comprises circumposing one end of the 10 skirt portion around the carrier body intermediate the stiffener plate and the end of the body portion and securing said end throughout its length to the carrier body, pulling the opposite end of the skirt over the secured end 15 to form a protuberant pocket, joining the sides of said skirt, and securing said opposite end of the skirt throughout its length to the carrier body.
8. The herein described method of attaching a skirt to a pneumatic dispatch carrier having a stiffener plate circumposed around its body portion adjacent to one end thereof, which comprises circumposing one end of the 20 skirt portion around the carrier body intermediate the stiffener plate and the end of the body portion and securing said end throughout its length to the carrier body, pulling the opposite end of the skirt over the secured end 25 to form a protuberant pocket, joining the sides of said skirt, compacting said pocket with packing material, and securing said opposite end of the skirt throughout its length to the carrier body.

- 30 9. A pneumatic dispatch carrier comprising a tubular body portion, and a skirt circumposed around said body portion adjacent to one end thereof, the circumposed ends of the skirt being secured to said body portion throughout their length, the central portion 35 of the skirt overlapping one of the secured ends thereof to form a protuberant pocket.

- 40 10. A pneumatic dispatch carrier comprising a tubular body portion, and a skirt circumposed around said body portion adjacent to one end thereof, the circumposed ends of the skirt being secured to said body portion throughout their length, the central portion 45 of the skirt overlapping the secured end thereof adjacent the end of the body portion 50 to form a protuberant pocket.

- 55 11. A pneumatic dispatch carrier comprising a tubular body portion, a skirt circumposed around said body portion adjacent to one end thereof, the circumposed ends of the skirt being secured to said body portion throughout their length, the central portion 60 of the skirt overlapping one of the secured ends thereof to form a protuberant pocket, and packing material disposed in said pocket to provide a protuberance of a desired configuration.

- 65 12. A pneumatic dispatch carrier comprising a tubular body portion, a stiffener plate circumposed around the body portion adjacent to one end thereof, and a skirt circum-

posed around said body portion with one end of the skirt secured throughout its length to said body portion intermediate the stiffener plate and the end of said body portion, the central portion of the skirt overlapping said 70 secured end thereof and the stiffener plate to form a protuberant pocket.

13. A pneumatic dispatch carrier comprising a tubular body portion, a stiffener plate circumposed around the body portion adjacent to one end thereof, a skirt circumposed around said body portion with one end of the skirt secured throughout its length to said body portion intermediate the stiffener plate and the end of said body portion, the central portion of the skirt overlapping said 75 80 secured end thereof and the stiffener plate to form a protuberant pocket, and packing material disposed in said pocket to provide a protuberance of a desired configuration. 85

Signed by me at Syracuse, N. Y., this fifth day of December, 1930.
